SPRAYING DEVICE

Carl Iddings, Staten Island, N. Y.

Application November 15, 1933, Serial No. 698,183

2 Claims. (Cl. 251—31)

My invention relates broadly to a spraying device and more particularly to an apparatus for spraying or applying liquids.

The primary object of my invention is to provide an apparatus for spraying or applying self propelled liquids that are described and claimed in my copending application Serial No. 634,598 filed Sept. 23, 1932.

An object of my invention is to provide a container with an air and gas tight seal having a valve and spray nozzle for use with a self propellant liquid.

Another object of my invention is to provide a liquid spraying device or apparatus that improves the economy in the use of sprays by eliminating all unnecessary spillage, evaporation and wastage, so that all but a very insignificant portion of the liquid, which necessarily remains in the container, can be effectively used.

A further object of my invention is to provide a spray device that requires no pumping or manipulative action and one that can be easily and efficiently handled.

Still another object of my invention resides in constructing in a spraying device a container having a valve that is not involved in its operation, easy to manufacture, for the most part from metal stampings, easy to assemble; simplicity with positive effectiveness governing the manufacture and use of the device.

With the above and other objects in view, the invention consists in the construction, combination and arrangement of parts as will be described more fully hereinafter.

Reference is to be had to the accompanying drawings forming a part of this specification, in which like reference characters indicate corresponding parts throughout the several views, and in which:

Fig. 1 is a central sectional view in plan of my improved container and valve.

Fig. 2 is a modified detail of my improved valve.

Fig. 3 is an extended nozzle of my improved valve.

Referring more particularly to the drawings, 10 indicates a container having neck 11 onto which is fastened cap 12 secured by means of collar 13 and gas tight gasket 44. Projecting upwardly from the cap 12 is a valve supporting tube or throat 14 securely fastened to a valve housing 15 by means of a gas tight joint. The valve supporting tube 14 is so connected to the valve housing 15 as to form a continuous internal passageway between the two parts. Extending 50 down from the throat 14 is syphon tube 16, preferably, but not necessarily, equipped with an enlarged end 17 which enlarged end is fitted in and secured to the valve supporting tube 14.

The syphon tube 16 extends downwardly to a point 18 near the bottom of the container and

preferably near one side as shown in the drawings. The purpose of placing the syphon tube near one side as shown is, of course, to permit, by slightly tipping the container toward this side, a more complete emptying of the container when used, thereby more fully utilizing the liquid contained therein.

The valve housing 15 has an enlarged end 19, around which extend flanged sides 20 of a valve head or cap 21, a nozzle 22 secured to the other end and intermediate the ends an opening 23 into the valve supporting tube 14. Between the opening 23 and cap 21, in the enlarged end 19, is a flexible diaphragm that has its perimeter fastened to the housing 15. Extending through and firmly secured to the diaphragm 24 is a valve stem 25 that has a threaded head 26 protruding through threaded aperture 27 in cap 21, thus permitting the cap to rotate on the threaded portion 26. To limit outward movement of cap 21, the end of the stem is flared as at 28, which end 28 is adapted to fit into a groove 29 of head 21 when the head is in the open position so as to form a practically continuous and smooth external surface.

Between opening 23 and nozzle 22 is a valve or seal 30 consisting of a valve disk seat through which stem 25 passes and a valve disk secured to the end of the stem. The valve disk is preferably made of a soft material 31, such as a resilient rubber, forced into a metal cup 32 that in turn is fastened to the end of stem 25. The disk seat consists of an annular ring 33 having a flanged periphery 34 secured to the inner walls of the housing 15 and a flared cone 35 extending outwardly from and around the opening 26 in the ring. Thus, stem 25 passes through a constricted opening 36 which is large enough to permit ready flow of fluids in the annular space between the stem and the annular ring and out the end of the cone 35 that is somewhat larger in diameter than opening 36.

The purpose of this construction is to provide a loose guide for the valve stem 25 thereby centering the stem and preventing an edge of the cone 35 from pressing against the seal at a point adjacent to the stem. Such a position adjacent to the stem 25 would be conducive to slow leakage and is accordingly avoided in the manner indicated.

Inserted in valve housing 15 between the seal 30 and the nozzle 22 is a block 37 with spiral cuts 38 such that fluids passing through the cuts and into an opening 39 just back of the nozzle 22 receive a swirling motion, thus assisting in the creation of a fine uniform spray.

To lock the valve so that it may not be accidentally opened and to further tighten the seal 30 to avoid losses by slow leakage, the head 21 is rotated about the threaded end 26 of stem 25

until the inner surface of the head 21 bears firmly against the end 19 of the valve housing 15.

The flexible diaphragm 24 is shaped with annular grooves for the purposes of providing greater flexibility and permitting a greater length of travel for the valve stem 25 between its extreme positions. This flexible diaphragm is also, preferably but not necessarily, mounted in the valve under slight compression so that the tension produced thereby tends to press the soft material 31 tightly against the outer edge of cone 35. In Figure 2 I have shown a bellows 42 in place of the diaphragm 24, however, the operation of these two spring seals are the same.

An important feature of this invention is that the area of the flexible diaphragm 24 and/or bellows 42 exposed to the fluids within the valve, is greater than the area of the seal 30 encompassed by the end of cone 35. The purpose of this feature is to utilize the pressure within the container which as hereinafter explained exceeds that of the atmosphere on the outside of the container, for assisting in maintaining a tight seal at 30 when the valve is not in operation. It is also my desire to have all joints and connections, with the exception of moving head 21, gas tight.

In the practical operation of my improved device, I first place within the container 10 a liquid 40 which is made in accordance with the method set out in my copending application Serial Number 634,598. The liquid has in solution a sufficient amount of a volatile component to create within the container a total absolute pressure in excess of one atmosphere when the container and its contents are at or near normal atmospheric temperature. The valve housing 15 is secured and sealed by cap 13 and made gas tight by means of gasket 44 and after the syphon tube 16, valve supporting tube 14 and cap 13, and valve housing 15 have been assembled, a continuous and always open passageway will be provided from the inside of the container 10, through the syphon tube 16, through the valve supporting tube 14 and into the central portion of the interior of the valve housing 15 through the opening 23. To operate the device the valve head 21 is rotated about the threaded portion 26 so that it travels away from the valve housing 15 until the head 21 reaches the dotted position 41 whereby its further movement is prevented by means of the stem end 28. To provide a spray as desired, the valve head 21 is now depressed by means of externally applied pressure in the direction of the nozzle 22 against the spring action of the diaphragm 24, and the pressure against it causing the stem 25 to travel in the same direction and carrying with it the cup 32 and insert 31 which thereby becomes separated from the valve seat or end of cone 35 and creates an open passageway for the liquid 40 which, due to its self propellant properties, is forced through the tube 16, through the open throat 14, through opening 23 into the inside of the valve housing 15, through the annular space between the ring opening 36 and the stem 25, through cone 35, through the annular space between the cup 32 and the valve housing 15, through the spiral slots 38 of the block 31, through the open conical space 39 and finally in the form of a fine and uniform spray through the nozzle 22. To stop the spraying the externally applied pressure upon the valve head 21 is released, permitting the diaphragm 24 to return to its normal position thereby moving valve stem 25 in a direction away from the nozzle

22 until the soft rubber 31 is brought into contact with its seat or outer edge of cone 35 thereby shutting off the flow of fluids to the nozzle 22. To lock the valve for the purpose of preventing slow leakage of the contents of the container during long periods of storage, or when the valve head 21 might be accidentally struck, the head 21 is turned on its axis so that it travels on the threads 26 in the direction toward the nozzle 22 until the inside face of the head 21 is brought into firm contact with the end of the valve housing 15. A further slight movement of the head 21 causes a slight pressure between the inner face of head 21 the end of the housing 15 which is transmitted by the stem 25 to the rubber insert 31 and the edge of cone 35. When it is desired to use the apparatus again for the purpose of creating a spray, it is only necessary to first unscrew the head 21 to the position 41, at which locality the apparatus is again ready for use.

The outer end of the valve tube 15 can be fitted with threads 45 as shown in Figure 3 suitable for attaching a flexible or inflexible extension 43 for conveying the vapors or mists to a greater distance from the container before releasing them through a nozzle to the atmosphere, or before directing them against the object to be sprayed. When using an extension, the nozzle 22 and/or the entire tube 15 could be moved to the outer end of the extension which can be attached either to the outer end of the valve housing 15 and/or to the valve supporting tube 14.

It will be understood that the above description and accompanying drawings comprehend only the general and preferred embodiment of my invention and that various changes in construction, proportions and arrangement of the parts may be made within the scope of this invention and appended claims without sacrificing any of the advantages of the invention.

What I claim is:

1. In a spraying device, a housing having an outlet port and an expanded portion opposite said port, a valve seat and valve disk adapted to bear against said seat for closing the outlet port, a flexible diaphragm hermetically sealed in tension to the inner surface of the expanded portion of the housing, the inner surface area of the diaphragm being greater than the inner area of said disk, an operating stem secured to the diaphragm and disk, and an inlet port in the housing between the diaphragm and valve seat whereby pressure passing through the inlet port directly contacts the inner surface of the diaphragm and, acting in conjunction with the tension of the diaphragm, exerts through said stem a positive force for holding the disk firmly against said valve seat.

2. In a spraying device, a housing having an outlet port, a valve seat and a valve disk adapted to bear against said seat for closing the outlet port, a flexible diaphragm hermetically sealed in tension to the inner surface of the housing, the inner surface area of the diaphragm being greater than the inner area of said disk, an operating stem secured to the diaphragm and disk, and an inlet port in the housing between the diaphragm and valve seat whereby pressure passing through the inlet port directly contacts the inner surface of the diaphragm and, acting in conjunction with the tension of the diaphragm, exerts through said stem a positive force for holding the disk firmly against said valve seat.

CARL IDDINGS.
